UNITED STATES PATENT OFFICE.

CHARLES W. MERRILL, OF BERKELEY, CALIFORNIA.

FILTER-PRESS.

1,093,345.

Specification of Letters Patent. Patented Apr. 14, 1914.

Application filed February 28, 1911. Serial No. 611,482.

To all whom it may concern:

Be it known that I, CHARLES W. MERRILL, of Berkeley, Alameda county, State of California, have invented an Improvement in the Construction of Filter-Presses, of which the following is a description.

The present invention relates to an improvement in devices for adjusting and supporting the sluicing pipe through which the sluicing liquid is introduced into the containers of pressure filters, and particularly to a device for adjusting and maintaining the position of the sluicing pipe from the exterior of the press without taking the units of the same apart.

The invention will be best understood by reference to the accompanying sheet of drawings, in which—

Figure 1 is a front elevation of one of the forms of containers of a filter press, of the type to which the present invention is applicable; and Fig. 2 is a side elevation of the device for supporting the sluicing pipe when in position in the press.

Similar letters refer to similar parts throughout both views.

In the drawings 1—1 is the exterior frame of the container which fits into the frame of the press between the filter plates in the ordinary manner; *d* is the horizontal feed channel located in the center at the top of the container through which the mixture and valuable components are introduced into the press; *6—6* are the drainage channels on either side, either or both of which channels may be used for the introduction of liquids, vapors or gases to the space behind the filter cloths if desired. The bottom 2 of the container or frame 1 is caused to slope downward from its opposite side inward toward the center, with the object of facilitating the discharge of the pulp resultant from

the sluicing. In order to support the sluicing pipe 19 within the press, I provide at any suitable number of intermediate points in the length of the pipe, throughout the press, supporting blocks, preferably of wood, each of which, by means of screws 21, is adjustable from the outside through the bottom of the press. The pipe 19 is fitted with 50 the collars 22 to bear on said blocks, so that the wear incident to any rotary movement imparted to the pipe will fall on the collars 22 and not on the pipe itself, and the latter will consequently not become weakened, and 55 will be always sufficiently supported to prevent the sagging which otherwise would occur and so affect the uniformity of the sluicing action in the different containers throughout the length of the pipe. 60

It will be observed by an examination of Fig. 1 that the block 20 is arranged to slide upward in a slotted opening in the projection 9^a on the bottom of the container, and by moving the screws 21, the block 20 can 65 be raised and lowered in the seat, and the pipe 19 adjusted without taking the parts apart.

I claim as my invention:

The combination with the rotary sluicing pipe of a vertical supporting block passing through an opening in the frame of a container, and devices for adjusting the same from the exterior of the press, substantially as described. 75

In testimony, that I claim the foregoing as my invention, I have signed my name in presence of two witnesses, this twenty-first day of February, 1911.

CHARLES W. MERRILL.
